DESIGN FOR A COMBINED BLOWER HOUSING AND PEDESTAL FOR OIL BURNERS OR THE LIKE

Reginald W. Beckett, Elyria, Ohio

Application December 15, 1938, Serial No. 31,784

Term of patent 14 years

To all whom it may concern:

Be it known that I, Reginald W. Beckett, a citizen of Canada, residing at Elyria, in the county of Lorain and State of Ohio, have invented a new, original, and ornamental Design for a Combined Blower Housing and Pedestal for Oil Burners or the like, of which the following is a specification, reference being had to the accompanying drawing, forming a part thereof.

In the drawing:

Figure 1 is a perspective view of a combined blower housing and pedestal for oil burners or

the like, showing the front and one side of my new design; and

Figure 2 is a perspective view thereof, showing the rear and other side.

The dominant features of my design reside in the portions shown in full lines in the drawing.

I claim:

The ornamental design for a combined blower housing and pedestal for oil burners or the like, substantially as shown and described.

REGINALD W. BECKETT.
